UNITED STATES PATENT OFFICE.

JULES CHAUMONT, OF WOODHAVEN, ASSIGNOR TO THE LALANCE & GROS-JEAN MANUFACTURING COMPANY, OF NEW YORK, N. Y.

CULINARY VESSEL.

SPECIFICATION forming part of Letters Patent No. 309,765, dated December 23, 1884.

Application filed April 4, 1882. (Model.)

To all whom it may concern:

Be it known that I, JULES CHAUMONT, a citizen of the United States, and a resident of Woodhaven, in the county of Queens and 5 State of New York, have invented certain new and useful Improvements in Culinary Vessels, of which the following is a specification.

My invention relates more especially to that class of culinary vessels which are employed for heating liquids and for preparing articles of food. It is advantageous to construct vessels of this character of such a form as to expose a heating-surface at the bottom which is as large as possible in proportion to 10 the capacity of the vessel, whereby the contents are heated much more quickly and efficiently. Vessels of this description have heretofore been made of cast-iron or pot-metal; but when thus formed of cast metal they are 15 not only inconveniently heavy, but their thickness is so great that heat passes through them with difficulty. Cast vessels are also fragile, and therefore liable to accidental injury. Vessels have also been formed from wrought- 20 iron by the processes technically termed "stamping" and "spinning," the sides and bottom of each vessel being formed separately and the parts afterward seamed or otherwise united together. Such vessels are of 25 less weight, and are in other respects much more desirable and convenient, than the cast vessels, but are liable, after having been in use, to give way at the seam which forms the junction of the sides and bottom, and thus 30 to become leaky and practically useless. Vessels have also been spun from a blank or single piece of sheet-iron or steel without a seam; but these have heretofore invariably been 35 made of a greater diameter at the mouth than at the bottom, thus affording but a comparatively small heating-surface. Vessels of this 40 form are also very liable to overflow when the contents are in a state of ebullition, as well as to be accidentally overturned.

45 My invention differs essentially from all these. It is formed by the process of spinning from a single piece of sheet-iron or steel, and therefore combines the strength, lightness, and durability of such a vessel with the mechanical stability and large proportionate 50 heating-surface, which is only obtainable by

means of the particular form of construction which I am enabled to give it, in which the diameter of the bottom of the vessel is considerably greater than that of its mouth.

55

In the accompanying drawings, Figure 1 is a vertical transverse section of a tea-kettle embodying my invention, and Fig. 2 is a view in elevation of a utensil designed for boiling milk, rice, &c.

60

In the figures, A represents the body of the vessel, the sides *a a* and the bottom *b* being formed from a single blank or piece of wrought-iron. The sides are contracted or drawn in toward the top in such a manner as to leave 65 an opening, *c*, the diameter of which is considerably less than that of the bottom *b*, as indicated by the dotted perpendicular lines *ff*, let fall from the opposite edges of the opening *c*. A vessel having a body of this general form may be adapted to various purposes, of which the two shown in the figures 70 are merely illustrations.

The vessel shown in Fig. 1, by the addition of a bail or handle, *e*, and a spout, *d*, forms a 75 convenient tea-kettle. A vessel of the same general form, with the addition of a suitable handle, *g*, as shown in Fig. 2, forms a saucepan or milk-boiler.

It is obvious that culinary and other vessels for heating liquids constructed in this manner possess great strength and durability, while their weight is comparatively small. The heating-surface is very great in proportion to the capacity of the vessel, while they 80 are not liable to overflow when boiling, or to be easily overturned by accident. These wares may be finished by any of the usual processes—such, for example, as tinning, japping, or enameling, as the application of 85 90 the high degree of heat necessitated by these operations will not in any way injure a seamless vessel.

I claim as my invention—

As a new article of manufacture, a seam- 95 less wrought-iron or steel vessel contracted at the upper edge by spinning, so as to make said upper edge of less diameter than the base.

JULES CHAUMONT.
